SHOE FITTING STOOL

William D. Locke, Beverly Hills, Calif.

Application March 31, 1939, Serial No. 265,071

1 Claim. (Cl. 34—239)

The present invention relates generally to stools employed in the fitting of shoes, and more particularly to a shoe fitting stool which includes means for drying the damp feet and hose of an individual being fitted for shoes.

It is a well-known fact that the feet of countless individuals perspire, no matter what the temperature, and that the feet of most individuals perspire during the warm days of the year. This fact gives rise to difficulties in the purchase of shoes, inasmuch as the dampness of the foot and encasing hose or sock renders accurate fitting difficult. Further, the linings of new shoes become stained and, in some instances, receive infectious growths which are more readily transmitted by dampness. Heretofore, powders, and the like, have been employed to alleviate the existing conditions, but such methods have not proved to be very satisfactory.

Therefore, an object of the present invention is to provide a shoe fitting stool which includes facilities for drying the feet of an individual being fitted for shoes.

Another object is to provide a combination shoe fitting stool and drier which functions both to receive a foot for fitting and to receive a foot for drying purposes.

Another object is to provide, in combination, a shoe fitting stool and foot drier.

Another object is to provide a combination shoe fitting stool and drier which is safe, inexpensive to manufacture, easy to operate, and thoroughly efficient in fulfilling all of the objects and advantages sought therefor.

Other objects and advantages will be apparent from the following description, taken in conjunction with the accompanying drawing, in which:

Fig. 1 is a plan view of a shoe fitting stool constructed in accordance with the teachings of the present invention;

Fig. 2 is a side view of the shoe fitting stool shown in Fig. 1, the movable footrest being shown in operative position;

Fig. 3 is a section on the line 3—3 of Fig. 1, the movable footrest being shown in retracted position;

Fig. 4 is a rear view of the shoe fitting stool, the rear screen being broken away in part for purposes of illustration;

Fig. 5 is a front view of the shoe fitting stool, a portion of the movable footrest being broken away to disclose the stationary footrest; and,

Fig. 6 is an enlarged section on the line 6—6 of Fig. 3.

Referring to the drawing more particularly by

reference numerals, 10 indicates generally the shoe fitting stool forming the subject matter of the present invention, which includes a casing 11 and a drying unit 12.

5 The casing 11 includes side walls 14 and 15, a bottom 16, and a top 17. The top 17 is covered with a suitable pliable material 18 secured to the top by tacks 19, or the like. A screen 20 closes the rear end of the casing 11, being secured by 10 screws 21, or the like, to cross pieces 22 extending between the sides 14 and 15.

A metal grill or stationary footrest 24 interiorly closes the front end of the casing 11, one edge abutting a transverse member or projection 25 secured to the bottom 16, the opposite end being secured by screws 26, or the like, to a transverse member 27 suitably anchored to the sides 14 and 15.

Disposed in adjacent relationship to the grill 24 20 when in one extreme position is a movable footrest or end cover 29 (Fig. 2), the forward end of which rests in a niche 30 formed in the transverse projection 25 and the sides of which rest on shoulders 31 formed in the edges of the sides 14 25 and 15. The shoulders 31 (Figs. 2 and 6) continue along the top edge of the sides 14 and 15. The movable footrest 29 includes a foot stop 32, upon which is disposed a handle 33. A stop element 34 threadedly engages the end of the rest 29 remote from the handle 33. The stop element 34 fits in a recess 35 (Fig. 3) in the top 17 to prevent removal of the movable footrest 29. A slot 36 (Figs. 1 and 3) is provided in the underside of the top 17 to receive the stop 34 in the movement 35 of the rest 29 into the position shown in Fig. 3.

Within the casing 11 are an electric fan 38, a resistance heater 39 disposed in front of the fan 38, both of which are mounted on the bottom 16, and an electric light 40 mounted on the side 14.

40 The three electrical units are connected by leads 41 in series and to a combination outlet and switch unit 42 (Figs. 2 and 4) mounted on the side 15. The unit 42 includes an operating lever 44 and an outlet 45. The outlet 45 may be separate from the switch, if preferred.

A roller 47 is connected to each under corner of the casing 11, which renders the stool 10 mobile.

The casing 11 and its cooperating elements may 50 be constructed of any suitable materials. The defining walls of the casing 11 may be connected by any suitable means or may be of integral construction.

Operation

The shoe fitting stool 10 is particularly adapted

to be used in a shoe store or other department. A salesman sits on the top 17 while the customer sits opposite the movable footrest 29. With the movable footrest 29 in the position shown in Fig. 2, the customer's feet are placed thereon and the shoes removed. The foot stop 32 provides an abutment for the heel of the foot or shoe.

After the shoes are removed from the feet of the customer, the movable footrest 29 is slipped back into the position shown in Fig. 3, whereupon the customer's feet are placed on the stationary footrest 24. The lever 44 is snapped to the "on" position. The heater 39 immediately begins to function, the warm air surrounding it being propelled forwardly against the feet and hose of the customer by the fan 38. As soon as the feet and hose of the customer are dry, the lever 44 is snapped to the "off" position, which deenergizes the electrical elements within the casing 11.

The light 40 provides a visible means for determining whether or not the device is on or off. The outlet connection 45 obviates the necessity of an attached cord, which is convenient and expeditious both for maintenance and use.

Ready access can be had to the electrical units within the casing 11 by removal of the screen 20. The movable footrest 29 can be removed by unscrewing the stop element 34. The stationary footrest 24 can be readily removed by removing the screws 26. The shoe fitting stool 10 is mobile through the medium of the rollers 47.

It is apparent that there has been provided a shoe fitting stool which is adapted to fulfill all of the objects and advantages sought therefor. It is to be understood that the foregoing description and accompanying drawing have been given by way of illustration and example and not for purposes of limitation, the invention being limited only by the claim which follows.

What is claimed is:

A shoe fitting stool for use in trying on shoes and the like comprising a casing of generally truncated rectangular configuration including side walls and a top wall, an end construction disposed at an angle to the horizontal comprising a grill and a movable cover, means under the top wall for slidably and swingably mounting said cover adjacent and beneath the top wall, said grill being adapted to receive the shoeless foot of an individual, said cover being movable from the position beneath the top wall through sliding and swinging action to a superposed position over the grill and being adapted to receive the foot of an individual in such position, said cover being adapted to be swingably and slidably moved from grill-covering to grill-exposing position, a fan disposed within the casing disposed to force air towards the grill, a heater element between the fan and the grill, and means for controlling the fan and heater element.
